DESIGN FOR AN EJECTOR SPRING FOR A CIGARETTE DISPENSER

Louis Kriegsfeld, Jersey City, N. J.

Application January 18, 1941, Serial No. 98,182

Term of patent 3½ years

To all whom it may concern:

Be it known that I, Louis Kriegsfeld, a citizen of the United States, residing at Jersey City, in the county of Hudson and State of New Jersey, have invented a new, original, and ornamental Design for an Ejector Spring for a Cigarette Dispenser, of which the following is a specification, reference being had to the accompanying drawing, forming part thereof.

Figure 1 is a plan view of an ejector spring for a cigarette dispenser showing my new design.

Figure 2 is a side elevational view thereof.

I claim:

The ornamental design for a ejector spring for a cigarette dispenser, as shown.

LOUIS KRIEGSFELD.
